SIMPLIFIED DEBUTANIZER FOR USE IN
ISOBUTYLENE EXTRACTION
George P. Baumann, Sparta, and Earle A. Nirmaier,
Maplewood, N.J., assignors to Esso Research and
Engineering Company, a corporation of Delaware
Filed June 15, 1960, Ser. No. 36,236
5 Claims. (Cl. 250—639)

The present invention relates to processes for extracting isobutylene from refinery C_4 streams to thus obtain concentrated n-butene feed streams for dehydrogenation. More particularly, this invention relates to improved processes of the type wherein isobutylene is absorbed in sulfuric acid, and the extract stream is either (1) diluted and stripped under conditions to obtain predominantly isobutylene monomer, or (2) heated to 250–300° F. to dimerize the isobutylene, followed by settling to separate the dimer from the sulfuric acid. In the former case the raffinate stream is distilled in a debutanizer tower to separate the n-butenes overhead from small amounts of alcohol and polymer and in the latter case the dimer and raffinate streams are combined and n-butenes are distilled overhead from both dimer and the said small amounts of alcohol and polymer.

Particularly this invention relates in the above described processes to the use of an improved debutanizer tower whereby the conventional caustic treat mixer and settler system ordinarily required prior to such a debutanizer to neutralize residual acids carried over in the raffinate (and dimer) feeds is eliminated. Most particularly this invention relates to an improved debutanizer tower wherein caustic treating is obtained within the tower itself by feeding caustic to the top of the tower and providing a large caustic holdup zone in the area of the feed plate of the tower.

The present invention provides large savings over the prior art processes. Thus, it is known that raffinate (and dimer) streams from the extraction process vary widely in acid level due to periodic minor upsets in the extraction and settling operations. To provide for these upsets large amounts of caustic have been required in the conventional caustic treat facilities to neutralize this acid when needed. Additionally it has usually been thought necessary to utilize Monel lining in the debutanizer tower to provide against acids carried over to the tower and against acids formed in the tower from acid esters. Thus these acid esters are only partially removed by caustic treating and they break down at the elevated temperature prevailing in the lower section of the tower. It has now been discovered that towers of the type described in this invention may be constructed of ordinary carbon steel, the large caustic holdup zone and the caustic flowing downwardly in the lower section of the column providing sufficient protection against corrosion.

The present process and apparatus will be more clearly understood from a consideration of the total process for preparing feed streams for dehydrogenation of normal butenes to butadiene. Thus, in the production of butadiene it is preferably that isobutylene be removed so that the butene feed stream may be dehydrogenated to extinction. A refinery C_4 stream obtained for example from steam cracking is absorbed in dilute sulfuric acid and the isobutylene acid extract is removed by settling. A preferred method for carrying out this process is described for example in U.S. 2,424,186 which patent is hereby included by reference. In general a C_4 fraction, containing paraffins, secondary, and tertiary olefins is absorbed in sulfuric acid preferably in two stages using a higher temperature in the first stage than in the second, a partially spent acid being used as the absorbent in the high temperature stage and fresh acid being used in the

2

low temperature stage. In the preferred form of the invention the C_4 hydrocarbon fraction, either in the gaseous or liquid state, is contacted with the partially spent acid from the low temperature stage at a temperature between 90 and 110° F., preferably 100° F., in any suitable manner. For example, resort may be had to agitation in a common vessel or to countercurrent flow. It is desirable when employing the C_4 fraction in a gaseous state to conduct the process in counter-current fashion through a packed tower as this system lends itself most readily to intimate distribution of the tertiary olefin in the absorbent. By using an acid extract as the absorbent which contains from 0.6 to 1.5 mols of isobutylene per mol of 100% sulfuric acid and operating at a temperature between 90 and 110° F., 65 to 85% of the isobutylene in the C_4 fraction is absorbed without any substantial absorption of the secondary olefins. The unabsorbed 15 to 35% isobutylene is then absorbed in fresh sulfuric acid having a concentration between 55 and 65 wt. percent, preferably 63 wt. percent if steel construction is to be used, at a temperature between 55° and 75° F., preferably 60° F. The contact between the acid and the olefin may be carried out in any manner as described above but is likewise preferably carried out in a packed column. The acid extract thus formed contains between 0.2 and 0.6 mol of isobutylene per mol of acid (based on 100% sulfuric acid) and is particularly suitable for use as the absorbent in the high temperature stage.

The C_4 raffinate stream (along with the extract dimer hydrocarbon stream if dimer is produced) is then debutanized in order to provide a C_5+ free normal butene stream for dehydrogenation.

The stream or streams from the extraction process supplied to the debutanizer will contain acid esters and free acid (normally about 0.2 wt. percent acid). Since the esters break down during heating both compounds result in corrosive conditions in the tower. According to the prior art corrosive conditions in the debutanizer tower were alleviated by caustic washing the feed stream in an orifice mixer and settler system prior to its being supplied to the tower. A considerable investment is involved in this prior art system since as previously discussed large capacity must be provided to take care of the highly acid conditions encountered during minor upsets. Further, it has been found in commercial operations using such a caustic prewash system that severe corrosion and operating difficulties are still obtained. Thus, for example, the following notes were recorded in connection with a commercial isobutylene extraction and dimerization operation.

(a) June 9, Unit Upset. "Acid circulation was stopped and the caustic increased to maximum available. Even after four dumps of caustic inventory the system was still acid. This meant we could not neutralize the ester content of the raffinate from the extraction settlers."

(b) June 9. "Rerun tower feed preheater tubes corroded through and the unit was shut down. Inspection showed that some jet tabs on the feed tray had been thinned down."

(c) December 19. "The system was fairly well lined out when a leak was discovered at a weld in the 3 inch spent butenes line to the caustic mixer downstream of the caustic addition point. The line was found to be seriously corroded and very thin on the upper side where the butenes entered for about 4 inches from the edge of the butene entry point. Minor corrosion on the upper part of the line continued for about 30 ft."

These illustrative problems and others reported in operating isobutylene extraction units will be avoided by utilizing the simple combined debutanizer and caustic treat tower of this invention.

Illustrative of the investment savings obtained by the

present invention it is estimated that for a typical isobutylene extraction and dimerization operation the conventional caustic treat system (which is eliminated in the present operation) costs about \$40,000 or 6% of the total investment of \$650,000 for an entire isobutylene extraction plant. Additionally in the preferred embodiment the need for Monel lining of the dimer tower is eliminated providing large additional savings.

The present invention will be more clearly understood from a consideration of the accompanying drawing depicting a preferred debutanizer tower and associated equipment. Although the tower may be either of the tray or of the packed type a bubble cap tray tower is described in the drawing. Turning to the drawing the normal butene raffinate stream from the isobutylene extraction settler is supplied to the tower 3 through line 1. If the process is of the type where isobutylene dimer is produced this dimer is also passed to the column (from the dimer settler where sulfuric acid is removed) through lines 2 and 1. Both of these streams are of course acidic. The single or the combined feed stream is supplied through a sparger (not shown) into the liquid on feed tray 4 located in the central section of the tower. This feed should preferably be supplied as a liquid although vapor or mixed vapor-liquid feeds can be used. The feed tray is of special design so as to be able to neutralize the equivalent of 20 minutes flow of 5 wt. percent entrainment of 65 wt. percent sulfuric acid. This large caustic holdup assures complete neutralization during the ordinary minor upsets in the isobutylene processes above described so that no pH change of the stream leaving this feed tray occurs. Dilute aqueous caustic solution is supplied to the upper part of the tower through line 3a. In a preferred embodiment open steam is supplied through line 4a and an additional sparger (not shown) into the liquid on the feed tray to provide feed preheat and additional steam is supplied through line 4b to the bottom of the tower to provide heat for the distillation. It should be noted that this steam should not be added directly to the feed stream due to the acid nature of said feed stream. Alternatively conventional reboilers and feed preheaters can be used. From the top of the tower the overhead C₄ stream is passed through line 5 to condenser 6 through line 7 to drum 8 and from said drum a part of the liquid stream is passed through line 9 back to the tower and the remainder of the stream is passed through line 10 to further processing. From the bottom of the tower the caustic and the heavier organic materials, e.g. small amounts of isobutene and alcohol along with the dimer, if both extraction and dimerization are obtained, are passed through line 11 to cooler 12. Thence, these materials are passed through line 13 to debutanizer bottoms caustic settler 14 where caustic is separated through line 15 and the heavier hydrocarbons are taken overhead through line 16 to further processing.

The present invention will be more clearly understood from a consideration of the following operating examples presenting operating conditions utilized in a preferred method of carrying out this invention.

I. COMPOSITION OF BUTENE RAFFINATE FEED STREAM FROM SULFURIC ACID EXTRACTION. PERCENT BY WEIGHT

	General	Preferred	Specific
Isobutylene	5-5.0	1.0-2.0	1.5
Normal butylenes	35-85	45-85	75
Butanes	10-65	14-55	23.5

II. COMPOSITION OF DIMER FEED STREAMS FROM ACID EXTRACT SEPARATOR, PERCENT BY WEIGHT

	30-90	60-80	70
Isobutylene Dimer	5-30	5-20	15
Isobutylene Butene Codimer	5-30	5-20	15

III. RELATIVE AMOUNTS OF TOWER STREAMS

	General	Preferred	Specific
5 Raffinate to Dimer Stream (where dimer is produced), percent by weight	300-800	500-700	600
Lb. of Caustic Solution/lb. of Feed	0.05-0.5	0.1-0.2	0.15
10 Composition of Caustic, wt. percent NaOH	1-10	2-5	3
Dimer Operation, Bottoms on Feed, percent by weight	10-50	20-40	25
Monomer Operation, Bottoms on Feed, percent by weight	1-15	2-10	5

IV. OPERATING CONDITIONS

15 Tower Pressure, p.s.i.g.	40-100	50-70	65
Temperature Bottom of Column, °F	230-300	240-290	265
Temperature, Top of Column, °F	70-190	80-150	124
Reflux Ratio	0.5:1-2:1	0.8:1-1.5:1	1:1
Open Steam Supplied, lb. Steam/lb. of Feed	0.2-0.7	0.3-0.5	0.35

V. DESCRIPTION OF COLUMN

Plates (Feed to Middle Section of Column)	10-40	15-30	20
Caustic Holdup on Feed Plate, Gallons Holdup/g.p.h. of Feed	.06-.30	.1-.2	.15

VI. C₄ STREAM OVERHEAD COMPOSITION, PERCENT BY WEIGHT

30 C ₄ 's	97.0-99.8	98.5-99.8	99.0
C ₄ 's	.2-3	.2-1.5	1.0
Di-trimer	0-.1	0	0

VII. DIMER BOTTOMS COMPOSITION (CAUSTIC FREE), PERCENT BY WEIGHT

35 C ₄ Trimer	5-35	10-30	18
C ₄ Dimer	60-90	65-88	.78
C ₄ 's	0-10	2-3	4

VIII. NON DIMER OPERATION BOTTOMS COMPOSITION, PERCENT BY WEIGHT

40 C ₄ 's	1-10	2-5	3
C ₄ Alcohol	20-40	25-35	27
Polymer	60-80	65-75	70

45 The present invention will also be advantageously utilized in extraction processes for separating isopentenes from normal pentenes. In these processes a refinery C₅ stream obtained from steam cracking, catalytic cracking etc. is absorbed in 55 to 65 wt. percent sulfuric acid, e.g. 63 wt. percent sulfuric acid and the extract stream is either stripped with steam under conditions to obtain high yields of the monomer or is reextracted with a hydrocarbon solvent to separate the isopentenes from the sulfuric acid fat solvent. In either event the raffinate stream from the acid extraction process is advantageously processed in the distillation system of the present invention. The normal pentenes raffinate feed stream to the tower will in general have compositions similar to those described for C₄ hydrocarbons. Thus, the ranges will be: for isopentenes, those shown for isobutylene; for normal pentenes, those shown for normal butylenes; and for pentanes those shown for butanes. Similarly the tower will be operated under the same conditions as those described above for the processing of butene raffinate feed streams.

50 60 65 The present invention will additionally be advantageously utilized in the production of secondary butanol. In this process a refinery C₄ normal butene stream obtained as above described (i.e. the overhead from the debutanizer) is absorbed in 75 to 85 wt. percent sulfuric acid in 2 or more stages. This feed stream will contain 25 to 95 wt. percent, e.g. 80 wt. percent, normal butenes, 0-5 wt. percent, e.g. 0.5 wt. percent, isobutenes, and the remainder paraffins. The sulfuric acid absorption will be similar to the 2-stage process described above in connection with the production of isobutylene or isobutyl-

ene dimer. In the production of butyl alcohol the extract stream is diluted with water to about 40-50 wt. percent sulfuric acid concentration and the diluted solution is then stripped with steam to obtain the alcohol. The raffinate stream is processed in the combined caustic treat debutanizer tower of this invention, under the conditions previously described for processing C₄ raffinate streams from isobutylene extraction.

The present invention can also be used in other processes where entrained acid and acid ester carryover are encountered. For example, in alkylation (to produce gasoline and to produce detergents), and in hydrocarbon condensation processes, problems of acid carryover into product fractionation equipment are encountered. In these processes, of course, olefins are reacted respectively with paraffins or with aromatics in the presence of a sulfuric acid, HF, BF₃, or AlCl₃ catalyst or are condensed with other olefins in the presence of a phosphoric acid on Kieselguhr catalyst.

The foregoing description contains a limited number of embodiments of the present invention. It will be understood that this invention is not limited thereto since numerous variations are possible without departing from the scope of the following claims.

What is claimed is:

1. A process for preparing normal butene which comprises contacting a C₄ hydrocarbon feed stream containing isobutylene and normal butenes with sulfuric acid to obtain absorption of a major portion of the isobutylene in said sulfuric acid, separating an extract stream from an acidic raffinate stream, feeding said raffinate stream directly to an intermediate hydrocarbon feed plate to a multiplate distillation column, feeding liquid caustic solution to a plate above said hydrocarbon feed plate to obtain a countercurrent flow of liquid caustic to the ascending hydrocarbon vapors in said distillation column, holding liquid caustic solution in said distillation column on said intermediate hydrocarbon feed plate in an amount and for a time sufficient to substantially neutralize the acids contained in said raffinate stream and recovering overhead substantially neutralized C₄ hydrocarbons.

2. The process of claim 1 wherein the raffinate stream is supplied to the column as a liquid and the holdup of caustic solution on said feed plate of the column is in the range of 0.06 to 0.30 gallons holdup/gallon per hour of feed.

3. A process for preparing a normal butene-containing stream suitable for conversion to butadiene by dehydrogenation which comprises contacting a C₄ hydrocarbon feed stream containing isobutylene and normal butenes with 55 to 65 wt. percent sulfuric acid to extract a major portion of the isobutylene in the acid and thereby also forming an acidic raffinate stream containing principally normal butenes and other hydrocarbons, separating said

extract stream from said raffinate, heating said extract to dimerize isobutylene, separating dimer from said extract, combining at least a portion of said dimer with said normal butene-containing acidic raffinate to form a dimer-containing raffinate, feeding said dimer-containing acidic raffinate directly to an intermediate hydrocarbon feed plate of a multiplate distillation column, feeding liquid caustic solution to a plate above said intermediate feed plate to obtain countercurrent flow of liquid caustic to the ascending hydrocarbon vapors in said distillation column, holding liquid caustic solution in said distillation column on said intermediate hydrocarbon feed plate in an amount and for a time sufficient to substantially neutralize said dimer-containing raffinate stream and separating C₄ hydrocarbons overhead from dimer and other heavier boiling materials.

4. The process of claim 3 wherein the feedstream to the tower is supplied as a vapor and the volume of caustic solution holdup on the feed plate is in the range of 0.06 to 0.30 gallons of caustic solution per gallon per hour of feed.

5. A process for the production of secondary butanol and separation of C₄ hydrocarbons which comprises contacting a substantially isobutylene-free C₄ hydrocarbon stream containing 25 to 95 wt. percent of normal butylenes with 75 to 85 wt. percent sulfuric acid to obtain an acid extract containing normal butylenes, separating said acid extract from the resulting acidic raffinate stream containing C₄ hydrocarbons, diluting said acid extract to about 40 to 50 wt. percent sulfuric acid concentration and stripping said extract to obtain secondary butanol, passing said acidic raffinate stream directly to an intermediate feed plate of a multiplate distillation column, feeding liquid caustic solution to a plate above said intermediate feed plate to obtain countercurrent flow of liquid caustic to the ascending hydrocarbon vapors in said distillation column, holding liquid caustic solution in contact with said raffinate stream on said intermediate feed plate for a time sufficient to substantially neutralize said raffinate and distilling C₄ hydrocarbons overhead from said distillation column.
